(57) **CLAIM**

The ornamental design for a wireless control module, as shown and described.

DESCRIPTION

The present application is related to U.S. Design patent application Ser. No. 29/525,165, filed Apr. 27, 2015 and entitled “Wireless Control Module”, and to U.S. Design patent application Ser. No. 29/525,912, filed May 4, 2015 and entitled “Wireless Control Module”, the entire contents of both of which are hereby incorporated by reference.

FIG. 1 is a front perspective view of an embodiment of a wireless control module showing our new design;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a bottom view thereof; and

FIG. 8 is a back perspective view thereof.

FIG. 9 is a front perspective view of another embodiment of the wireless control module showing our new design.

FIG. 10 is a front view thereof;

FIG. 11 is a right side view thereof;

FIG. 12 is a back view thereof;

FIG. 13 is a left side view thereof;

FIG. 14 is a top view thereof;

FIG. 15 is a bottom view thereof; and,

FIG. 16 is a back perspective view thereof.

The broken lines shown in the Figures are environmental and form no part of the claimed design.
